FRONT FASTENING MEANS FOR CORSETS

Irving R. Versoy, New Haven, Conn., assignor to
 The Berger Brothers Company, New Haven,
 Conn., a corporation of Connecticut

Application February 28, 1939, Serial No. 258,969

2 Claims. (Cl. 2—38)

This invention relates to corsets and articles of a kindred character designed for personal wear, and relates particularly to the means for securing the adjacent edges of such body-encircling garments, particularly when the opening is at the front of the garment.

Various means, such as clasps, for example, have been employed to secure together the adjacent or abutting edges of garments of this character, and in the past it has been common to arrange a plurality of such clasps upon stay members which extend along the edges of the garment, a plurality of the fastening means being secured to a single stay. As such garments normally project below the waist it is not practical to extend these clasp supporting stay members throughout the vertical length of the garment as it would not be sufficiently flexible adjacent the opening. It has been common, therefore, to provide such stay members from the top of the garment to a point below the waist line and to secure the edges of the opening below this point by fastening members which are individually secured to the garment, so that the garment edges may flex between these members. In other words, the upper portion of the garment is provided with stay members to which a number of clasps or similar securing means are secured, and the lower portion of the garment may be closed by hooks and loops or hooks and eyelets which are not secured to stays but are secured individually to the fabric of the garment itself.

The present invention relates particularly to the improvement in the securing means employed at the lower or flexible portion of the garment adjacent the opening. In the past it has been difficult to provide fastening members which would not become detached or which would not be bulky or unsightly when in use, and at the same time could be readily secured by the wearer of the garment.

One object of the present invention is to provide a securing means for the edges of the opening of a corset or like garment, which securing means may be readily secured when the garment is put on and at the same time any danger of accidental detachment of the securing members will be obviated.

Another object of the invention is the provision of securing members individually secured to the edges of the opening of a corset or like garment, of such character that the members will lie comparatively flat upon the surface of the garment and not produce undue thickness at that

point, and at the same time will hold the abutting edges of the garment in a securely closed position.

To these and other ends, the invention consists in the novel features and combinations of parts to be hereinafter described and claimed.

In the accompanying drawing:

Fig. 1 is a front elevational view of the front portion of a corset provided with my improvements;

Fig. 2 is a front elevational view of the securing means at the upper portion of the garment;

Fig. 3 shows the cooperating securing means at the lower or flexible portion of the garment;

Fig. 4 is a sectional view through line 4—4 of Fig. 1 showing the securing elements in the position occupied at the beginning of the movement to release the loops from the studs, and

Fig. 5 is a side elevational view of one of the loop members which constitutes one of the cooperating securing members.

To illustrate a preferred embodiment of my invention I have shown in Fig. 1 the front portion of a corset comprising sections 10 and 11, these sections meeting along the line 12 which constitutes the opening in the garment and in the form shown extends throughout the vertical length thereof.

Stay members 13 and 14 are provided in the proximate edges 10 and 11, these stay members, as shown in Fig. 1, extending from the upper edge of the garment to a point approximately half way to the lower edge. It will, of course, be understood that the length of the stay members 13 and 14 will be varied as desired according to the particular style of garment to which the invention is applied.

Secured to the stay member 14 are a plurality of clasp members 15 which are provided with openings 16 of keyhole shape to cooperate with headed studs 17, secured to the stay members 13. These members are of usual form and no further description thereof will be necessary. It will be obvious that the upper portion of the garment over which the stay members 13 and 14 extend, will be relatively rigid at the area covered by these members.

Below the stay members 13 and 14 it may be desired that the garment be flexible so as to accommodate itself to the different positions of the limbs or body of the wearer. It is, therefore, not practical to extend the stays 13 and 14 throughout the length of the garment but it is preferred to provide individual fastening members over this lower area so that the garment may flex between such members.

These fastening elements or members consist, in

the form shown, of loops 18 of the shape shown in Fig. 3, which cooperate with headed studs 19 secured by riveting or other suitable means to relatively broad base plates 20, the studs being secured by their base plates at the edge of one section 10 of the garment while the loops are secured adjacent the edge of the other section 11 of the garment.

The loops 18 are provided with a relatively large intermediate portion 21 and a smaller end portion 22, so that the head 23 of the stud 19 may be received in the enlarged portion 21 and the shank thereafter slipped into the smaller portion 22 of the loop, the head being sufficiently large so that it will not slip through this portion of the loop. The sides of the front portion 22 of the loop are substantially parallel and will receive therebetween quite freely the shank of the stud 19. As its rear end the loops 18 may be provided with eyes 24 which may be secured by rivets 25 to a strip of tape 26 in preparation for attaching them to the garment section 11. As shown in Fig. 4, one or more plies (two, as shown) of a thin fabric 27 may be folded over the tape 26, the loops 18 projecting through openings 28 in the folds of these members so that they may extend over the edge of this section of the garment. The outer fabric of the garment, as shown at 29, is also brought up over the base portion or eyes of the loop and turned under, as shown at 30. A similar disposition is made of the back fabric 31 of the garment so that the loops project between folded edges of the plies of fabric 30 and 31 but project through openings of the plies of fabric 27. It will also be noted that as shown in Fig. 3 these openings pass over the larger portion 21 of the loop into the restricted portion between the large portion and the eyes 24, so that when the loops are forced through the openings they will tend to remain in position while the stitching is being accomplished. After the tape 26 is placed in position between the plies of fabric, as shown in Fig. 4, the edge of the garment is suitably stitched to hold the tape and plies of fabric in place as well as to hold the loops in the proper position.

The base plates 20 having the studs 19 thereon are placed between the plies of fabric at the edge of the garment section 10, with the studs 19 projecting through openings in the plies of fabric above the plates to be exposed upon the surface of the garment where they may cooperate with the loops 18.

As shown in Fig. 5, the loops 18 are not flat in a longitudinal direction but are arch-shaped, having their highest point intermediate their ends, as shown at 32 in this figure, and the two ends sloping downwardly from this point. This longitudinal bend or arch shape of the loops is important in preventing any accidental detachment of these members from the studs. As will be apparent from Fig. 1, the edges of the garment close in close juxtaposition and in order to bring the heads 23 of the studs into the larger portion of the loop to detach it, it is necessary to bring the edges of the garment together or to lap the edge of the portion 11 over the section 10. It is necessary, therefore, to raise the section 11 slightly, as shown in Fig. 4, above the plane of the section 10 so that it will slip thereover. When the section 11 is raised, as shown in Fig. 4, due to the arch shape of the loop, the upper surface of the loop contacts with the lower surface of the head 23 of the stud, as shown at

the point 33. This causes the tip end or toe of the loop 34 to be forced downwardly against the outer surface of the section 10 of the garment, thus engaging this surface frictionally and compressing it or biting into it to some extent, so as to resist any further relative movement between the two sections. It is necessary, therefore, that the section 11 be positively raised and moved in overlapping position over the section 10 before the loop can be detached from the stud. Thus, as it is necessary for the edge of the section 11 to be moved over the section 10 in order to detach the fastening members, and as the section 11 must be raised above the section 10 in order that this be done, there is no likelihood of the fasteners becoming undone accidentally, and thus made, they form a reliable and secure means for holding the edges of the garment together.

However, they can be readily detached when the actions described are positively performed and as the stud fits loosely in the loop portion 22 there will be less resistance offered to the release of the stud from the loop when it is desired to open the garment.

The element 18 may be considered as comprising a base portion which is provided with the eyes by which the element is secured to the tape 26, and a loop portion which projects forwardly from the edge of the section to which the element is attached to embrace the stud 19, and it will be noticed, particularly from Figs. 4 and 5, that, as so considered, the loop portion lies in a plane making an obtuse angle with the plane of the base portion, so that when the corset is worn and the base portion is held by the garment substantially in the plane of the garment, the loop portion will project inwardly (or downwardly) toward the surface of the adjacent section surrounding the stud, so that the tip will be in frictional engagement with the surface of the fabric surrounding the stud and prevent play between the two sections.

While I have shown and described a preferred embodiment of my invention, it will be understood that it is not to be limited to all of the details shown but is capable of modification and variation within the spirit of the invention and within the scope of the appended claims.

What I claim is:

1. In a fastening means for a corset having sections with edges designed to be secured in abutting relation, a series of headed studs individually secured adjacent the edge of one section to project from the surface thereof, and a series of cooperating members individually secured in spaced relation to the proximate edge of the other section whereby the garment sections may flex therebetween, each of said members comprising a base portion and a loop portion, said base portion having eyes by which it may be secured between the plies of the section to which it is attached, with the loop portion projecting therefrom to engage the corresponding stud and seat it adjacent the end of the loop, said base portion lying in a plane making an obtuse angle with the plane of the stud seating part of the loop portion whereby, when the loop embraces the stud and the base portion lies in the plane of the garment, said loop portion is directed toward the surface of the section carrying the stud with the tip of the loop biting into the fabric around the stud.

2. In a fastening means for a corset having sections with edges designed to be secured together in abutting relation, relatively rigid stay

members secured to said sections adjacent their edges and extending downwardly therealong from the upper edges of the garment but terminating short of the lower edge thereof, each 5 of said stay members carrying a plurality of co-operating fastening members, means for securing together the edges of said sections below said stay members, said means comprising headed studs secured individually adjacent the edge of one of said sections in spaced relation, a tape secured adjacent the edge of the other section, co-operating fastening elements secured in spaced relation to said tape, said elements each comprising a base portion secured directly

to the tape and a loop portion to project therefrom and engage said studs, said loop portion joining said base portion at an obtuse angle, and a strip of fabric folded around the outer edge of the tape and secured at its free edges to the fabric of the garment section, said strip having openings in its folded edge through which the loop portions of said elements project, and said loop portions being enlarged in width intermediate their ends and of reduced width adjacent said openings whereby they are held in position during manufacture of the garment by the edges of said openings. 10
